(57) **CLAIM**

The ornamental design for a ceiling fan blade iron, as shown and described.

DESCRIPTION

FIG. 1 is a perspective view from below of a ceiling fan blade iron in accordance with my design, illustrating the environment of said blade iron;

FIG. 2 is an enlarged perspective view from below of the ceiling fan blade iron in accordance with my design, illustrating the environment of said blade iron;

FIG. 3 is an enlarged side elevation view of the ceiling fan blade iron in accordance with my design, illustrating the environment of said blade iron;

FIG. 4 is an enlarged bottom plan view of the ceiling fan blade iron in accordance with my design, illustrating the environment of said blade iron;

FIG. 5 is an enlarged distal view of the ceiling fan blade iron in accordance with my design, illustrating the environment of said blade iron; and,

FIG. 6 is an enlarged proximal view of the ceiling fan blade iron in accordance with my design, illustrating the environment of said blade iron.

The broken lines showing environmental structure are for illustrative purposes and form no part of the claimed design.
